UNITED STATES PATENT OFFICE.

WILLIAM MILTON BROWN, OF JOHNSTOWN, PENNSYLVANIA, ASSIGNOR TO
THE LORAIN STEEL COMPANY, A CORPORATION OF PENNSYLVANIA.

ELECTRIC SWITCH.

No. 853,220.

Specification of Letters Patent.

Patented May 14, 1907.

Application filed February 20, 1905. Serial No. 246,438.

To all whom it may concern:

Be it known that I, WILLIAM MILTON BROWN, of Johnstown, in the county of Cambria and State of Pennsylvania, have invented a new and useful Improvement in Electric Switches, of which the following is a full, clear, and exact description, reference being had to the accompanying drawings, which form a part of this specification.

My invention has relation to electric switches, and is designed to provide a switch which, while adapted for use in various relations, is particularly intended for use in a system of car wiring such as shown in my Patent No. 594,379, for controlling the circuits of the series and shunt coils as therein shown and described. That is to say, my invention is designed to provide a switch structure operated by a single handle, for controlling the battery connection of the series coils, and also the circuit of the shunt coils.

With this object in view, my invention consists in the novel construction, arrangement and combination of parts, all substantially as hereinafter described and pointed out in the appended claims, reference being had to the accompanying drawing, in which

Figure 1 is a plan view of the switch; Fig. 2, is a vertical section on the line II—II of Fig. 3; Fig. 3, is a similar view on the line III—III of Fig. 2; Fig. 4, is a sectional plan view of the switch (with the spring I removed) on the line IV—IV of Fig. 3, showing the contacts d' in closed circuit position, and the contacts e' in open circuit position.

The letter A designates a suitable casing or enclosure, divided horizontally into two compartments, the lower compartment containing a cartridge fuse B, and the upper compartment the switch proper, now to be described. Vertically journaled in said upper compartment, is a shaft C, upon which are loosely mounted two switch members D and E. These switch members preferably consist of bodies of insulating material, the one having embedded therein a central hub d, and a conductor d', and the other a hub e, and conductor e'. The conductors d' and e' have their end portions projected beyond the peripheries of the respective bodies to form contacts, which are adapted to co-operate with fixed contacts to complete the circuits through the switch. These fixed contacts are designated by the letters f, g, h and i, respectively,

the contacts f and g are provided with indents to receive the semicircular ends of the conductor d' of the switch member D.

Between the two members D and E, the shaft C has rigidly secured thereto a clutch member F, having the clutch teeth f², f³. To co-operate with these clutch teeth, the hubs d and e are recessed; hub d being recessed at a², to receive the tooth f², and hub e being recessed at e² to receive the tooth f³. Attached to the hub e at one end, and to the casing at the opposite end, is a spring G which normally holds the switch member E in the open circuit position shown in Figs. 3 and 4. Pivotated to an upward extension of the hub d, is a link H, which curves around the shaft C, and has a spring I connected to its free end, said link being so arranged that when the switch member D is in circuit-closing position, as shown in Figs. 3 and 4, the pull of the spring I tends to hold the said member in that position, while if said member D be turned to the right a short distance, sufficient to bring the line of pull of said spring to the other side of the center, said spring will immediately act to throw said member to wide open circuit position.

The casing A, has the boss A' formed with a guide slot for the lug j of the switch operating handle J. This slot has a portion a' in one plane, and a second portion a² in a slightly higher plane. In the normal position of the switch, shown in Figs. 3 and 4, the lug j is at the central portion of said slot, or against the offset connecting the two portions thereof. If the handle be moved to the left, the member D is not affected, but the engagement of the clutch tooth f² with the hub e, turns the member E to circuit closing position, where it is held so long as the lever is held; but as soon as the lever is released, the spring G immediately returns said member to the position shown in Figs. 3 and 4.

It will be seen from the foregoing that the circuit through the member D (which is the circuit of the shunt magnet coils described in my said patent) is normally closed, while the circuit through the member E (which is the battery circuit of the series coils) is normally open, but may be momentarily closed by turning the switch handle to the left. To open the circuit through the member D, it is necessary to raise the handle until its lug j engages the higher portion a² of the

guide slot. When so shifted the handle is moved to the right, thereby (through the clutch connection) actuating the member D. The spring I now acts upon said member to effect a quick break of the circuit:

L L' designates the circuit wires of the shunt coil circuit, one of which passes through the fuse B, said wires being connected to the fixed contacts *f* and *g*. M M' designate the connections of the battery circuit, which are connected to the contacts *h* and *i*.

The details of construction and arrangements which I have herein shown and described may be varied without affecting my invention, and hence I do not wish to be limited to such specific form of switch.

Having thus described my invention, what I claim as new and desire to secure by Letters Patent is:—

1. In a switch of the character described, the combination of a movable shaft, two independent switch members loosely mounted on said shaft, and clutch means whereby movement of said shaft in one direction will move one of said members, and movement of the shaft in the opposite direction will turn the other of said members.

2. In a switch of the character described, the combination of a movable shaft, two independent switch members loosely mounted on said shaft, contact devices co-operating with the said members whereby the circuit through one member is normally closed and the circuit through the other member is normally open, and co-operating clutch devices carried by said shaft and members, whereby movement of said shaft in one direction from the normal position will close the open circuit without opening the closed circuit, and whereby movement in the opposite direction from said normal position will open the closed circuit without closing the open circuit.

3. In a switch of the character described, the combination of a shaft, a clutch member

rigidly secured thereto, two independent switch members loosely mounted on the said shaft and having clutch hubs arranged to co-operate with said clutch member, a spring connected to one of the said members and acting to resist movement thereof and to effect its return movement, and a spring connected to the other member and forming a lock therefor, and also an actuating means.

4. In a switch of the character described, a movable shaft having the switch members D and E loosely mounted thereon, and provided with clutch hubs, a clutch member secured to said shaft between the members D and E and arranged to operatively engage the said members by reverse movements of the said shaft, a returning spring connected to the member E, and the dog H and spring I connected to the member D, substantially as described.

5. In a device of the character described, stationary conducting parts, a plurality of movable conducting parts, independently movable carriers for said parts, and a common means for independently moving said carriers to establish or break the connections of the relatively movable and stationary conductive parts.

6. In a device of the class described, stationary conducting parts, a plurality of movable conducting parts, independently movable carriers for said movable parts, a concealing structure for said conducting parts, and means extending without the concealing structure for independently moving said carriers to establish or break the electrical connection of the relatively movable and stationary conducting parts.

In testimony whereof, I have affixed my signature in presence of two witnesses.

WILLIAM MILTON BROWN.
